UNITED STATES PATENT OFFICE

SOLOMON HELFGOTT, OF NEW YORK, N. Y.

JEWEL-SETTING TOOL

Application filed January 15, 1927. Serial No. 161,407.

This invention relates to improvements in watch maker's tools or instruments and more particularly to a novel and improved jewel setting device employed in setting roller 5 jewels and pallet stones of very small watch movements.

One of the objects of my invention is to provide a tool or instrument designed to retain and set very small jewels such as roller 10 jewels and pallet stones, and particularly under such conditions where the size of the jewel and its setting is too minute to permit of its proper handling by the present type of tools or instruments employed. 15 Extreme difficulty has always been experienced by watchmakers in setting roller jewels and pallet stones in very small watch movements. In some instances, the jewels are only a fractional part of a millimeter in 20 diameter. In the present practice, the jewels are handled by needle point pincers, rendering it difficult to seize and manipulate so as to position it within the setting. The work is very tedious, requires a steady hand 25 and trained eye. The very fine jewel being highly polished invariably flies out of the pincers with the result that it is often necessary to handle four or five jewels before one may be 30 properly set. It therefore must be understood that in very small and delicate watch movements, the roller jewels and pallet stones are correspondingly minute and more difficult to handle so that what may appear to be 35 a simple operation under ordinary conditions becomes a problem when the size renders the jewels difficult to set.

To enable others skilled in the art to more fully comprehend the underlying features of 40 my invention that the same may be better understood, reference is had to the accompanying drawing showing a preferred embodiment of my invention wherein

Fig. 1 is a top plan showing the tool or instrument.

Fig. 2 is a side view showing the jewel guard.

Fig. 3 is a view similar to Fig. 1 showing the manner of setting the jewel in the watch 50 mechanism, shown in dotted lines.

Fig. 4 is a longitudinal sectional view through the tool or instrument.

Fig. 5 is an enlarged end view.

Fig. 6 is a perspective view on an enlarged scale showing a watch jewel. 55

Referring now to the drawings wherein like reference characters designate corresponding parts throughout the several views, 5 designates a substantially tubular or cylindrical, machined tool or instrument body 60 having an internally threaded end bore 6. The top surface of the body 5 is rabbeted or cut to provide a recess as at 7 to receive a flat, 65 slideable, push plate 8 which is substantially the width of the body. 65

Within the body there is provided a feed screw 9 having a knurled end 10, said screw cooperating with the threaded end of the body. The non-threaded end 11 of the feed screw is equipped with an extension 12, considerably less in diameter than the main body of the screw and is grooved radially as at 13 to receive a connecting screw 14 passing through the push plate 8. Consequently, any movement imparted to the feed screw advances or retards the push plate relative to the outer end of the tool or instrument body. 70 75

The grooved extension fits within a socket 15 in the end of a guide rod 16 within the said tool or instrument body, said rod having an aperture to receive a pin 17 connecting the push plate 8 therewith. It will therefore be seen that the feed screw and the guide rod are connected for movement with each other in advancing the push plate toward the 80 end of the instrument but that the feed screw may rotate relative to the guide rod when the push plate is withdrawn and abuts the wall 18 of the tool body proper as shown more clearly in Figs. 1 and 4. 85 90

The side of the tool or instrument body is also recessed to receive a spreader plate 19 preferably of resilient metal which is fixedly secured adjacent the outer end thereof. The spreader plate is L-shaped toward the front 95 end forming a flange portion 20 adapted to lie in contact with the flat top surface 7. This flange is cut to provide a cam wall 21 which assists in temporarily controlling the clamping of the jewel 22 preliminary to position- 100

ing or feeding the same into the aperture of the watch movement.

The outer end of the push plate is rounded off to cooperate with the cam wall or cam surface of the spreader plate, and is provided with a pointed extension 23 which is adapted to engage the rear end of the jewel and advance it forwardly or beyond the end of the tool from the position shown by Fig. 1 for instance to that shown by Fig. 3.

The jewel which is provided with at least one flat, plane surface is positioned in the recess 22^a in the body 5 at its outer end and adjacent the inner wall of the L-shaped end of the spreader plate. When the push plate is in the position shown by Fig. 3, the pin 25 rides along the cam surface 21 and consequently spreads the spreader plate. On the other hand, as the feed screw is advanced, the pin 25 recedes, so to speak from the cam surface, and the inherent resiliency of the metal causes the spreader plate to move inwardly, thus engaging the side of the jewel. Further movement of the feed screw and the push plate necessarily advances the jewel beyond the end of the tool or instrument so that it may be projected into the seat or aperture of the roller or the pallet as the case may be.

The roller jewel, which I have illustrated in Fig. 6 has a flat, plane surface and a beveled top, so that when positioned on the plane surface of the recess 22^a of the tool or instrument adjacent its end, the said jewel may be held in clamping relation by the L-shaped extension 25 and projected into the roller. In other words the recess for the jewel is shaped so that although the jewel is highly polished and very smooth, nevertheless it will not fly out when once positioned. However, in setting the jewels in a pallet for instance, it is necessary to provide means for retaining the jewel which is substantially square shaped in cross section. To that end, I have provided a latch plate 26 having a finger piece 26^a, said plate being held or fastened to the spreader plate by a pivot screw 27. The latch plate is also equipped with an L-shaped extension 28 adapted to overlie the L-shaped extension of the spreader plate and the recess in which the jewel is first positioned before it is advanced or fed into the pallet setting. The latch plate thus prevents the roller jewel from becoming dislodged or moved upwardly while in the said recess as said jewel is being pushed or urged beyond the end of the tool into the roller or pallet. As shown in Fig. 6 the roller jewel is an irregular object having a plane and a curved surface and under ordinary conditions the roller jewel would tend to fly out of the recess 22^a when considerable pressure is applied at its end when being forced into the roller or pallet above referred to. It will thus be seen that for setting the jewel in the roller the latch plate may be raised or swung on its pivot and in setting the jewel in the

pallet, the latch plate is pushed down and brought over the recess in which the jewel is positioned before it is advanced into the pallet. Consequently, the same tool or instrument by the use of the latch plate permits the setting of a jewel in two different elements of a watch movement.

While I have shown and described my invention with some degree of particularity, it must be further pointed out that the actual size of the instrument or tool and the extreme minuteness of the jewel which the instrument or tool has been designed to handle is of extreme importance. The drawings therefore have been considerably enlarged for the sake of clearness since the actual instrument or tool is only about one third the size. The showing of the roller jewel is also greatly exaggerated since it is of a size that permits of handling and manipulating only by the aid of an eye magnifying glass and needle point pincers or other small instruments whereby it may be set preliminary to feeding or forcing it into the roller or pallet. It necessarily follows that the steps and operations in setting a very minute jewel into a roller or pallet in a very small watch movement is very different from the old practice employed. While the jewel may be picked up with the pincers by reason of the high polish and smooth surface, this instrument is not practical for forcing or urging the jewel into the setting. Consequently, when the jewel is placed in the above described tool, it may be easily handled and manipulated by bringing the end into proximity with the aperture of the roller or pallet for setting. As the jewel is advanced, it is held at all times by the instrument with the result that it cannot fly out.

While I have shown a preferred form of my invention, it will be understood that various changes in the details of the structure described may be made. I therefore reserve the right to make such changes and alterations in the details of the structure shown as may fall within the scope of the subject matter being claimed.

Having shown and described my invention what I claim as new and desire to secure by Letters Patent is:

1. A jewel setting instrument comprising a tool body cut away to form a surface to receive a sliding plate and a rabbeted recess adjacent one end thereof for receiving an individual roller jewel therein, a spreader plate attached to one side of the body, one end of said plate having a side extension forming a clamping means for a jewel positioned within the said recess, a cam surface on the side extension, a plate sliding on the cut away surface cooperating with the spreader plate for opening the same, one end of said sliding plate engaging the end of the jewel and a feed screw for advancing the sliding plate whereby the jewel may be forced outwardly beyond

the end of the body and into the setting of a roller or pallet of a watch movement.

2. A jewel setting tool comprising a tool body having a recess open on two sides on one face thereof and at its end for receiving the plane surface of a roller jewel therein, a spreader plate for retaining a roller jewel within said recess in proximity to one end of said body, said spreader plate having a side extension for engaging the jewel to clamp the same in said recess, a latch plate carried by the spreader plate, said latch plate having an extension overlying the said recess to prevent the jewel from moving upwardly and out of the recess, a movable plate engaging the inner end of the jewel and a feed screw for advancing said plate gradually whereby the jewel may be forced into the jewel setting of a roller or pallet of a watch movement.

In testimony whereof I affix my signature.
SOLOMON HELFGOTT.
